UNITED STATES PATENT OFFICE.

PATRICK McGUNNIGLE, OF NEW YORK, N. Y.

MOUTH-PIECE FOR SPEAKING-TUBES.

SPECIFICATION forming part of Letters Patent No. 374,746, dated December 13, 1887.

Application filed March 13, 1886. Serial No. 195,158. (No model.)

To all whom it may concern:

Be it known that I, PATRICK McGUNNIGLE, of the city, county, and State of New York, have invented a new and valuable Improvement in Mouth-Pieces for Speaking-Tubes; and I do hereby declare that the following is a full, clear, and exact description of the construction and operation of the same, reference being had to the annexed drawings, making a part of this specification, and to the letters and figures of reference marked thereon.

Figure 1 is a perspective view of my new and improved speaking-tube mouth-piece, showing the whistle closed. Fig. 2 is a front elevation of the same, showing the whistle open. Fig. 3 is a sectional plan view reversed, the section being taken just below the whistle and shaft thereof in the position of Fig. 1. Fig. 4 is a similar view showing the whistle closed, and Fig. 5 is a sectional elevation showing the construction of the parts of the frame of the mouth-piece.

The invention will first be described in connection with the drawings, and then pointed out in the claim.

The mouth-piece is composed of the two main parts A A', connected together back of the bell a by a lap joint, the front part, A, being reduced in diameter, as shown at b, the part A' being enlarged to form a flange, as shown at b', to form the joint. In the reduced portion b and flange b' are formed correspond-

ing slots or openings, c c', on both sides of the mouth-piece and exactly in line with the center or diameter thereof. These openings are 35 to receive and form journals for the shaft F of the whistle B, which shaft is exactly central to the whistle. In this manner the shaft and whistle have their axis at the diameter of the mouth-piece, and thus avoid hinges and other 40 details of construction incident to the ordinary form of mouth-piece.

The indicator E is pivoted or hinged to the outer surface of the whistle, as shown clearly in the drawings, and the handle C to the shaft 45 of the whistle counterweights the whistle, so that it normally closes the mouth-piece, as shown in Fig. 1.

Having thus described my invention, what I claim as new, and desire to secure by Letters 50 Patent, is—

A mouth-piece for speaking-tubes, composed of the two parts A A', formed with diametrical openings c c', in combination with the shaft F, supported in said openings, and whistle B, 55 attached centrally to the shaft F, substantially as described.

In testimony that I claim the above I have hereunto subscribed my name in the presence of two witnesses.

PATRICK McGUNNIGLE.
